MACHINE FOR LASTING THE TOE PORTION
OF UPERS IN THE MANUFACTURE OF
SHOES

John Hoza, Belcamp, Md.

Application April 20, 1940, Serial No. 330,780
In Czechoslovakia November 2, 1938

12 Claims.

(Cl. 12—14)

This machine relates to a machine for automatically lasting the toe portion of uppers by pulling-over the toe portion, drawing it tight, forming it to the last and attaching it to the insole in the manufacture of boots, shoes and other like articles of footwear (hereinafter and in the claims referred to as shoes).

An object of the invention is to provide mechanism for correctly forming the toe portion of shoe uppers throughout the whole of its extent in the manufacture of shoes of different sizes.

Another object is to smooth out the effects of unequal forces, or non-uniformities, in the material of the toe portion to be attached.

Another object is to ensure that, in the wiping action applied to the margin of the toe portion, i. e. the lasted edge, the wipers close simultaneously on the entire margin to be attached.

Another object is to spread or distribute the material of the toe portion in a smoothly uniform manner.

Another object is to make provision whereby the hammers, which insert the fasteners to attach the toe portion to the insole, act directly and not through special top slides to reduce their stroke.

Another object is to make it practicable to use fasteners whose length is the same as the thickness of the materials to be attached.

Further objects of the invention will be apparent from the following description and claims.

A machine for lasting the toe portion of shoe uppers will now be described by way of example with reference to the accompanying drawings, in which:

Fig. 1 is an elevation of the entire machine.

Fig. 2 is a sectional elevation of the toe-forming device in operative position.

Fig. 3 is a sectional plan illustrating forming cheeks of said device.

Fig. 4 is a sectional plan illustrating a wiper device in its normal, or inoperative, position.

Fig. 5 is a section of the line II—II of Fig. 4 illustrating the attaching device for driving fasteners into the materials to be attached.

Fig. 6 is a detail view illustrating an operating mechanism for the presser arm.

The machine comprises mainly the toe-forming device, the wiper device and the attaching device.

The device for forming on the last K (see Figs. 1, 2 and 3) the toe portion of the leather upper is arranged at the end of a presser arm 1 which serves as a carrier for said device and associated parts. The device includes forming cheeks 2

5 abutting against one another for lateral pivotal movement about the point A of contact. These cheeks are guided in their movement by arcuate tracks 3, the centre of arcuity of these tracks being the point A. Lugs 4 extending from the cheeks 2 are urged apart by a spring 5 on a pin 6 passing through both of said lugs. The spring 5 acts on the cheeks to form the material at the toe of the upper smoothly and accurately by a wiping action in conformity with the last, the cheeks being adaptable for the manufacture of shoes of different sizes.

Non-rotatable adjustment nuts 7, 8 screwed on the pin 6 serve to limit the extent of separation of the lugs 4 or the clamping action of the cheeks, according to the style of the shoe. Adjustment of these nuts is effected by a finger knob 9 on the pin 6.

10 The centre A about which the cheeks 2 turn is adjustable with reference to the point of the toe portion. Adjustment is effected by means of a dove-tail guide 10 which forms a connection between the cheeks and their pivotal supporting bracket and which is controlled by an adjustment screw 11.

15 The working parts of the toe-forming device are all carried by the aforesaid pivotal supporting bracket, which is pivotally attached by a pin 12 to the arm 1, the bracket and parts carried thereby being depressed by a spring 13 on a set-screw 14. This screw 14 serves mainly in connection with displacement of the toe-forming device, the range of displacement thereof at the centre A being denoted by x in Fig. 2.

20 There is also provided at the end of the presser arm 1 an adjustable presser 15 which is formed as the holder of a pad or cushion 16. This presser is mounted in a guideway at the end of the arm 1, being depressed by a spring 17 on an adjustment screw 18. The spring 17, acting through the cushion 16, serves to smooth out non-uniformities in the material of the toe portion.

25 The presser arm 1 is pivotally attached by a pivot pin 19 to the frame of the machine and is operatively connected by a link 20 with operating mechanism which may be of any appropriate and well known design, such as shown for example in Figure 62 of the patent to Pym, 2,039,448. A suitable operating mechanism is shown for illustrative purposes in Fig. 6, in which A' is an actuating cam for the bell crank B' pivotally mounted at C' and coupled with the link 20 by means of a cushioned and slideable connecting means D'. The particular design of the

operating mechanism forms no part of the present invention, and may be of any construction desired so long as it is capable of oscillating the arm 1, through the link 20.

On the machine frame and underneath the pivot pin 19, guiding means for the wiper device is provided. This device includes a guide block or unit 21 which is rearwardly movable on the frame. At the front of the block 21, wiper elements 22, 23 with nail-receiving holes are mounted, these elements being laterally pivotable about the centre B (Fig. 4) under the guidance of arcuate tracks 24. The elements 22, 23 are formed peripherally with teeth 25 which mesh with small toothed pinions 26 meshing also with toothed racks 27. Each of the racks 27 is connected by a pin 28 to a rod 29 which is guided for movement in the machine frame. In the forward movement of the block 21, that is movement away from the machine and towards the last, the rod 29 moves with the block until said rod abuts against a stop 30, which is borne by a pin 31 on an adjustable lever 32 (Fig. 1). When abutment occurs, the racks 27 come to rest, so that continuation of the block's forward movement results in rotation of the pinions 26. Thus, the wiper elements 22, 23 and the wiper shears close towards one another. This closing motion takes place as the centre B approaches the point C at the toe point (Fig. 4). The distance from the centre B to the point C, in the normal or inoperative position of the block, corresponds to the distance between the abutting portion of the rod 29 and the stop 30. Thus, during the continued forward movement of the block 21, the closing wiper elements 22, 23 cause the toe portion material which is to be marginally attached to be uniformly wiped throughout its entirety to the extent of the attachment distance D.

After the wiping action of the elements 22, 23 on the toe portion of the shoe upper, and subsequent attachment thereof to the sole, the block 21 is withdrawn rearwards. In the withdrawal of the block, a shoulder on the rack 27 moves against a stop 33 which is attached by a screw 34 to the frame of the machine. This stop acts to reopen the elements 22, 23 during the remainder of the return of the block. The stop 33 must be so adjusted on the frame that, when the return of the block is completed, the inner faces of the elements 22, 23 are closed against one another along the axis I—I, which is the longitudinal axis of the machine.

An attaching device is mounted on, for up-and-down movement in relation to, the wiping elements 22, 23 by means of guide pins 35 (Figs. 4 and 5). This device includes guide plates 36 wherein are provided openings which serve as holders for the hammers 37. The hammers extend into guides in the plates 22, 23, said guides serving also to receive fasteners in the form of tacks H. In view of non-uniformities in the upper material to be pinched up, the hammers are adjustable in height by means of adjustment screws 38. The hammers are acted upon by springs 39 to bias them toward retracted position. The guide plates 36 also are acted upon by springs 40 to bias them toward retracted position on the pins 35. A press table is provided in association with a support for the toe end of the last K to force the plates 36 upwards against the yielding resistance of the springs 40.

A pincer or gripper assembly is provided on the base plate of the machine, one unit thereof being shown at b (Fig. 4) and others (not shown) be-

ing arranged opposite at b and on the machine axis at a. These pincers may be of any suitable design, similar, for example, to those shown in the patent to Pym, 2,039,448, or in the patent to McFeely, 663,777, or in applicant's copending application, 330,778, filed April 20, 1940. The pincers are movable up and down and serve to seize and draw out the toe-portion material to be formed and attached. Within the pincer assembly the previously mentioned support for the last is arranged. In this support there is a hollow shaft wherein is arranged the guide pin or shaft of the previously mentioned press table, which acts upwardly under pressure on the guide plates 36 for insertion of the nails H. The heel end of the last is supported by another support on the base plate of the machine.

The operation of the machine is as follows:

With the material placed upon and drawn over the last, the presser arm 1 swings downwards, with the result that the centre A of the toe-forming cheeks 2 comes close against the upper material and, in the consequential pivotal movement (within the limits x, Fig. 2) of the toe-forming device about the pin 12, the forming cheeks slide closely along the form of the last and downwardly as far as the plane of the hammering action on the shoe (see Fig. 2). As shown, the margin O of the shoe upper projects from below the forming cheeks. Thus, the cheeks spread themselves smoothly over the toe portion of the upper. Simultaneously, the presser cushion 16 becomes firmly seated upon the last.

After the end of the downward movement of the presser arm, the block 21 slides forwards in the toe-to-heel direction. The margin O projecting from below the cheeks 2 is thus operated upon by the wipers, which are forced to pivot towards one another. Then the margin O is attached by the action of the press table in rising against the hammer guide plate 36. The tacks H, which are filled into the holes in the elements 22, 23 and which stand close against the material to be attached, are driven in this manner into the material. After the attachment operation, all the parts return to their original position, in which the holes in the wiper elements are again filled with tacks for the next shoe, and the cycle of operations is repeated.

I claim:

1. A machine for forming the toe portion of shoe uppers, such machine comprising a frame, a supporting means on said frame for a last, an arm pivotally mounted on said frame and adapted to be mechanically lowered and raised to and from an upper on a last on said supporting means, a toe-forming device pivotally attached to said arm for engagement with the toe portion of the upper and having spring means yieldingly resisting pivotal movement of said device when forced by lowering of said arm to engage the toe portion, said device comprising toe-portion-engaging cheeks contacting one another at a point and pivotable to and from one another about said point, means arcuate about said point for guiding said cheeks in their pivotal movement, spring means urging said cheeks to pivot towards one another and screw-adjustment means limiting the pivotal movement of said cheeks towards one another.

2. A machine as claimed in claim 1, characterized by a pivotal bracket whereon the arcuate cheek-guiding means is provided, said bracket being a component of the toe-forming device, a guide connection between said bracket and

cheek-guiding means, a screw adjustment for adjusting said cheek-guiding means along said connection to-and-from a last on the supporting means, and an adjustable connection between said bracket and the arm to limit the extent of pivotal movement between said bracket and arm.

3. A machine as claimed in claim 1, comprising also a cushion adapted to engage the toe-portion of a shoe-upper on a last on the support, a holder on which said cushion is provided, a guideway on the arm for said cushion holder and adjustable spring means depressing said holder so that the cushion will bear on and smooth out non-uniformities from the toe-portion when the arm is lowered.

4. A machine for forming the toe portion of shoe uppers, such machine comprising a frame, a supporting means on said frame for a last, an arm pivotally mounted on said frame and adapted to be mechanically lowered and raised to and from an upper on a last on said supporting means, a toe-forming device including toe-portion-spreading cheeks and attached to said arm for engagement of said cheeks with the toe portion of the upper, and means to engage the margin of the spread toe portion for attachment of the margin to the shoe insole, said engaging means comprising a block guided on said frame for movement to-and-from the toe portion, wipers mounted on said block to pivot to-and-from one another about a point of contact, means articulate about said point for guiding said wipers in their pivotal movement, rack-and-pinion mechanism actuated by said block during an extent of the movement thereof, adjustable abutment devices for transmitting movement from said block to said mechanism, and connections between said mechanism and said wipers for pivoting them in engagement with the entire margin of the spread toe portion to be attached.

5. A machine as claimed in claim 4 including also attachment means for attaching the toe portion of a shoe upper to the insole by fasteners, said attachment means comprising guide plates respectively mounted below the wipers for upward movement under pressure, spring means yieldingly resisting upward movement of said guide plates, fastener-receiving guides in the wipers, hammers mounted in said guide plates and entering said guides to support fasteners inserted therein, and screw devices for adjusting the mounting of said hammers in said guide plates, the arrangement being such that upward movement of said guide plates forces the hammers to drive the fasteners from the guides into the toe portion and insole.

6. A machine for forming the toe portion of shoe uppers, such machine comprising a frame, a supporting means on said frame for a last, a carrier mounted on said frame and adapted to be mechanically moved to and from an upper on a last on said supporting means, a toe-forming device attached to said carrier for engagement with the toe portion of the upper and having spring means yieldingly resisting movement of said device when forced by said carrier to engage the toe portion, said device comprising toe-portion-engaging cheeks pivotable away from one another by engagement with the toe portion to spread themselves smoothly thereover, and spring means urging said cheeks to pivot towards one another.

7. A machine for forming the toe portion of shoe uppers, such machine comprising a frame, a supporting means on said frame for a last, a

carrier mounted on said frame for movement to and from an upper on a last on said supporting means, and a toe-forming device attached to said carrier for yieldingly resistant engagement with the toe portion of the upper in the movement of said carrier, said device comprising toe-portion-engaging cheeks pivotable away from one another by engagement with the toe portion to spread themselves smoothly thereover and means yieldingly urging said cheeks to pivot towards one another.

8. A machine for forming the toe portion of shoe uppers, such machine comprising a frame, a supporting means on said frame for a last, a carrier mounted on said frame for movement to and from an upper on a last on said supporting means, and a toe-forming device attached to said carrier for yieldingly resistant engagement with the toe portion of the upper in the movement of said carrier, said device comprising a bracket pivotally mounted on said carrier, a guide element connected to said bracket and adjustable relatively thereto in the direction to-and-from the last on said supporting means, toe-portion-engaging cheeks arcuately guided by said guide element and pivotable away from one another by engagement with the toe portion to spread themselves smoothly thereover, and means yieldingly urging said cheeks to pivot towards one another.

9. A machine for forming the toe portion of shoe uppers, such machine comprising a frame, a supporting means on said frame for a last, a carrier mounted on said frame for movement to and from an upper on a last on said supporting means, a cushion holder mounted on said carrier, spring means pressing said holder yieldingly towards the toe portion of the upper, a cushion on said holder to engage the toe portion, and a toe-forming device attached to said carrier for yieldingly resistant engagement with the toe portion concomitantly with said cushion in the movement of said carrier, said device comprising toe-portion-engaging cheeks pivotable away from one another by engagement with the toe portion to spread themselves smoothly thereover, and means yieldingly urging said cheeks to pivot towards one another.

10. A machine for forming the toe portion of shoe uppers, such machine comprising a frame, a supporting means on said frame for a last, a carrier mounted on said frame for movement to and from an upper on a last on said supporting means, a toe-forming device attached to said carrier for engagement with the toe portion of the upper in the movement of said carrier, said device comprising toe-portion-engaging cheeks pivotable with yielding resistance away from one another by engagement with the toe portion to spread themselves smoothly thereover, and means to engage the margin of the smoothly spread toe portion for attachment of the margin to the shoe insole, said engaging means comprising an assembly guided on said frame for movement to-and-from the toe portion, margin-engaging wipers mounted on said block to pivot to-and-from one another, and mechanism actuated by said unit in the movement thereof to pivot said wipers to and from one another.

11. A machine as claimed in claim 10 including also attachment means for attaching the toe portion of a shoe upper to the insole by fasteners, said attachment means comprising guide plates respectively connected to the wipers for yieldingly resistant movement under pressure towards the

toe portion, fastener receivers in the wipers, and hammers movably mounted in said guide plates and entered into said receivers to support fasteners inserted therein.

12. A machine for forming the toe portion of 5 shoe uppers, such machine comprising a frame, a supporting means on said frame for a last, a carrier mounted on said frame for movement to and from an upper on a last on said supporting means, a toe-forming device attached to said 10 carrier for engagement with the toe portion of the upper in the movement of said carrier, said device comprising toe-portion-engaging cheeks

pivotal with yielding resistance away from one another by engagement with the toe portion to spread themselves smoothly thereover, wipers movable into engagement with the insole-engaging margin of the smoothly spread toe portion, guide plates respectively connected to the wipers for yieldingly resistant movement under pressure towards the toe portion, fastener receivers in the wipers, and hammers movably mounted in said guide plates and entered into said receivers to support fasteners inserted therein.

JOHN HOZA.
